UNITED STATES PATENT OFFICE.

GEORGE W. CARR, OF ST. LOUIS, MISSOURI.

RAILWAY-CAR.

1,161,025.

Specification of Letters Patent. Patented Nov. 23, 1915.

Application filed April 4, 1914. Serial No. 829,651.

To all whom it may concern:

Be it known that I, GEORGE W. CARR, a citizen of the United States of America, residing at the city of St. Louis, State of Missouri, have invented a certain new and useful Railway-Car, of which the following is such a full, clear, and exact description as will enable any one skilled in the art to which it appertains to make and use the same, reference being had to the accompanying drawings, forming part of this specification.

My invention relates to a railway car, and, more particularly, to that class of cars which is adapted to run upon an elevated track and to be controlled by means exterior to the car itself.

In the accompanying drawings, which illustrate a portion of a railway car embodying one form of my invention, Figure 1 is a vertical longitudinal section; Fig. 2 is a section taken on the line 2—2 of Fig. 1; Fig. 3 is a top plan view showing the means for applying the brake; Fig. 4 is a side view of some of the parts shown in Fig. 3; Fig. 5 is a sectional view showing the parts illustrated in Fig. 4; Fig. 6 is a detail view of the cam for releasing the brake mechanism; Fig. 7 is an enlarged horizontal section of a portion of the car; and Figs. 8 and 9 are enlarged detail views showing the clutch mechanism and flexible connections therefor.

Like marks of reference refer to similar parts in the several views of the drawings.

10 represents a truck frame. This frame 10 is carried by a pair of casings, each consisting of a lower part 11 and another part 12 bolted together, as best shown in Fig. 1 of the drawings. Journaled in each of the casings is an axle 13 provided with a pair of wheels 14 adapted to run upon the track 15. Arranged midway between the axles 13 is a motor 16. This motor 16 is adapted to be thrown into operative connection with one or the other of the axles 13 so as to drive the car in the one or the other direction. As the connections between the motor 16 and the axles 13 at each end of the car are duplicate, only one need be described.

Mounted on the axle 13 is a bevel gear 18 which meshes with a bevel pinion 19. This pinion 19 is mounted on the end of a short shaft 20, best shown in Fig. 7 of the drawings. Keyed to this shaft 20 is a disk 21, shown in detail in Fig. 8. This disk 21 is

provided with openings 22 to receive pins 23 carried by a hollow member 24 forming one portion of the clutch mechanism for connecting the shaft 13 with the motor 16. This clutch member 24 surrounds one end of the shaft 20 and is provided with a concave recess 25 bearing against a convex washer 26 which also surrounds the shaft 20 and bears against the disk 21. This bearing, together with the fact that the pins 23 fit loosely in the openings 22, allows of a certain amount of pivotal movement between the clutch member 24 and the disk 21, or, in other words, a flexible connection is secured between these parts. Coöperating with the clutch member 24 is a second clutch member 28 which is provided with a roller bearing 29 which coöperates with a ball 30 formed on the reduced end 31 of the shaft 20. The clutch member 28 is keyed to a shaft 32. This shaft 32 has keyed to its opposite end a disk 33. Adjacent to the disk 33 is a disk 34 which is provided with a central opening 35 receiving a ball 36 formed on the reduced end 37 of the shaft 32.

Each of the disks 33 and 34 is provided with pins 38, preferably three in number. These pins 38 pass through slots 39 formed in the opposite disks, as best shown in Figs. 8 and 9 of the drawings. These pins, together with the ball connection 36, not only allow the shaft 32 to be moved longitudinally so as to bring the two parts of the clutch into operative connection, but also allow a slight lateral pivotal movement so that the two parts of the clutch may be brought into proper contact even if the various shafts are not in perfect alinement.

In order to move the two parts of the clutch into operative connection, a collar 40 loosely surrounds the shaft 32. Interposed between this collar 40 and the hub of the clutch member 28 is a coil spring 41. End thrust bearings 42 are preferably placed between the collar and the disk 33 and between the spring 41 and the hub of the clutch member 28. The collar 40 is actuated to throw the clutch into and out of operative connection by means of a suitable handle 43. The disk 34, hereinbefore referred to, is keyed to the end of the shaft 44 which is driven from the motor 16. It will be understood that by throwing the clutch at one end of the car into operative position, and that at the other end of the car out of opera-

tive position, the car will be driven in one direction, while by reversing the clutches, the car will be driven in the other direction.

In order to provide braking means for the car, a pinion 46 engages with the bevel gear wheel 48 at a point opposite to the pinion 19 hereinbefore described. This pinion 46 is secured to the end of a shaft 47, the opposite end of which is supported by a bracket 48 carried by the truck frame 10. Mounted on this shaft 47 is a conical member 49 forming the rotary portion of a clutch brake. The member 49 co-operates with a member 50 which forms the non-rotary portion of the clutch brake. This member 50 is loosely mounted on the shaft 47 and is prevented from rotating by means of a cross-bar 51 sliding in guides 52 carried by the truck frame 10. In order to apply the brake, it is necessary to move the non-rotary portion 50 longitudinally. To accomplish this, I provide a sleeve 53 between which and the member 50 is a coil spring 54. This spring 54 is engaged by a yoke 55 carried by a lever 56. This lever 56 is pivoted at 57 to the truck frame 10, as best shown in Fig. 3 of the drawings. The opposite end of the lever 56 has a slotted connection with one arm 59 of a bell crank lever. The opposite arm 60 of this bell crank lever is provided with a downwardly projecting roller 61. The bell crank lever is carried by means of a bracket 62 bolted to the truck frame 10, as best shown in Fig. 4 of the drawings. The roller 61 carried by the arm 60 of the bell crank lever is adapted to come into contact with the cam track 63 so as to apply the brake at any suitable point, as, for instance, at the top of a grade. In order to hold the brake in applied position, the end of the arm 60 is provided with a boss 64 having a recess adapted to be engaged by a locking pin 65 carried in a bracket 66 secured to the truck frame 10. This locking pin 65 is normally moved downwardly by means of a coil spring 67. It will be evident that after the recess in boss 64 is engaged by pin 65, the brake will be held in applied position. In order to release the brake at any suitable point, as, for instance, at the bottom of a grade, the locking pinion 65 is provided with a laterally projecting rod 69 which is adapted to be engaged by a cam track 70, shown in detail in Fig. 6 and moving upwardly so as to release the brake.

75 is a frame forming the lower portion of the car body. This body frame 75 is supported above the truck frame 10 by means of coil springs 76 which enter pockets 77 in the upper portion 12 of the casings hereinbefore referred to. In order to guide the body frame 75 in its up and down movement, I provide guide pieces 77, preferably one at each side of the springs 76, as best shown in Fig. 1 of the drawings. These guides 77

are secured to the body frame 75 and make sliding contact with the inner faces of the truck frame 10. Each of the guides 77 is provided with an over-turned portion 78, as best shown in Fig. 2. These over-turned portions 78 are adapted to contact with the lower faces of the truck frame 10 and thus limit the upward movement of the body frame 75. In order to prevent longitudinal movement between the frames 10 and 75, I secure blocks 79 to the truck frame 10, as best shown in Fig. 1, so as to make sliding contact with the edges of the guides 77.

The operation of my car will be evident from the above description. When the car is to be started out upon a trip, one of the levers 43 is moved so as to throw its clutch into operative position, while the other of said levers is moved into position to throw its clutch out of operative position. In this manner, the car can be run in either direction desired. The connection between the motor 16 and the driving wheels is such that the clutches may be properly applied, no matter whether the various portions of the shaft are in perfect alinement or not. This is essential, not only because it is difficult to secure perfect alinement in the first instance, but also because the slight cambering of the car under varying load would disturb the alinement when not properly secured.

As has been above described, the brakes are automatically applied and released by means of the cam tracks arranged at proper intervals along the track 15.

Having fully described my invention, what I claim as new and desire to secure by Letters-Patent of the United States is:

1. The combination with a car frame of two sets of car wheels, a motor, gearing actuated from said motor for driving one set of wheels in one direction, and the other set in the other direction when the motor is running in the same direction, and means for throwing one set of wheels into engagement and the other set of wheels out of engagement with the motor.

2. The combination with a car frame, of two sets of car wheels, a motor, gearing actuated by said motor for driving one set of wheels in one direction and the other set in the other direction when the motor is running in the same direction, a clutch mechanism for throwing one set of wheels into and the other set out of engagement with the motor.

3. The combination with a car frame, of a pair of casings secured to said frame, an axle mounted in each of said casings, and provided with car wheels, a bevel gear mounted on each of said axles within the casing, a motor, gearing for driving said bevel gears from said motor, said gearing being arranged to drive said bevel gears in op-

posite directions when the motor is running in the same direction, and means for throwing one of said bevel gears into and the other out of operative connection with the motor.

4. The combination with a car frame, of a pair of wheels, a motor for driving said wheels, a clutch arranged between said motor and wheels for connecting and disconnecting same, and a flexible connection allowing lateral motion interposed between the clutch and motor.

5. The combination with a car frame, of a pair of wheels, a motor for driving said wheels, a clutch arranged between said motor and wheels for connecting and disconnecting the same, a flexible connection interposed between the clutch and wheels, and a second flexible connection interposed between the clutch and motor.

6. The combination with a car frame, of a pair of wheels, a motor having its shaft arranged longitudinally of the car, gearing for driving said wheels from said motor, a clutch mechanism for throwing said gearing into and out of operative connection with the motor, a pair of disks, one secured to said shaft, and pin connections be-

tween said disks, said connections being arranged to allow lateral motion.

7. The combination with a car frame, of a pair of wheels, a motor arranged with its shaft extending longitudinally of the car, a divided shaft for driving said wheels from said motor, a pair of disks each connected to one part of said shaft, pin connections between said disks, a clutch mechanism, a third disk carried by said shaft, and pin connections between said third disk and one pair of said clutch mechanisms.

8. The combination with a driving member, of a driven member, a longitudinal extending shaft communicating power from said driving member to said driven member, said shaft including two end portions and a central portion, said central and end portions having ball connections, and disks carried by said portions and having pin connections with each other.

In testimony whereof, I have hereunto set my hand and affixed my seal in the presence of the two subscribing witnesses.
